United States Patent Office

Des. 223,697
Patented May 30, 1972

223,697

TIE ROD WRENCH

Walter Harold Finley, Orange County, Calif.
(200 N. Gilbert St., Apt. 12, Anaheim, Calif. 92801)

Filed Dec. 7, 1970, Ser. No. 26,341

Term of patent 14 years

Int. Cl. D8—05

U.S. Cl. D8—21

FIG. 1 is a perspective view of the tie rod wrench showing my new design;

FIG. 2 is a side elevational view thereof;

FIG. 3 is a rear elevational view thereof;

FIG. 4 is a bottom plan view thereof;

FIG. 5 is a sectional view thereof taken along line 5—5 of FIG. 2 above; and

FIG. 6 is a sectional view thereof taken along line 6—6 of FIG. 2 above.

I claim:

The ornamental design of a tie rod wrench, substantially as shown.
